Patented Dec. 3, 1957

181,600

CAULKING GUN

Gustav W. Nilsson, Mentor, Ohio

Application July 9, 1956, Serial No. 42,179

Term of patent 14 years

(Cl. D62—2)

Fig. 3

Fig. 4

Fig. 1 is a side elevational view of a caulking gun, showing my new design;

Fig. 2 is a top plan view thereof,

Fig. 3 is a front end elevation; and

Fig. 4 is a rear end elevation.

I claim:

The ornamental design for a caulking gun, substantially as shown.
